MACHINE FOR FASTENING UPPERS TO
INSOLES

Karl Engel, Swampscott, and Charles S. Kinney,
Middleton, Mass., assignors to United Shoe
Machinery Corporation, Paterson, N. J., a cor-
poration of New Jersey

Application March 9, 1938, Serial No. 194,804

15 Claims. (Cl. 12—4)

This invention relates to machines for fastening uppers to insoles, and is herein illustrated as applied to a machine constructed generally as disclosed in United States Letters Patent No. 5 1,558,737, granted on October 27, 1925 upon an application of R. F. McFeely, certain portions of the machine being constructed as further disclosed in Letters Patent No. 1,852,015, granted on April 5, 1932 upon an application of J. C. 10 Jorgensen. Such machines are commonly used for lasting the heel ends of shoes, and an object of the present invention is to adapt a machine of that type for convenient use to fasten the heel parts of uppers to insoles in the manufacture 15 of shoes in which the heel parts of the uppers are unattached to the foreparts and are formed or molded substantially in final shape before they are assembled with the insoles. It is to be understood, however, that the invention in its more 20 general aspects is not limited to the manufacture of shoes of that particular character and is also not limited to machine organizations of the particular type disclosed in the above-mentioned Letters Patent.

25 A heel-end-lasting machine of the above-mentioned type comprises wipers movable to wipe the margin of the heel end of the upper inwardly over the insole, means for driving a row of fastenings to fasten the upper to the insole, a heel 30 band for clamping the upper about its heel end, and a work support movable to present the work to the means which operates thereon. It will be evident that such a machine is appropriate for use to fasten the previously formed or molded 35 heel parts of uppers to insoles in the manufacture of shoes in which the heel parts are unattached to the foreparts, since the heel band will position the heel part in proper relation to a last or other form on which the insole and the 40 heel part are mounted, the wipers will press the inturned flange of the heel part close against the insole, and the fastening means will fasten the flange in proper relation to the insole. It is, however, inconvenient for the operator to control 45 the short loose heel part with his fingers until the work support has carried the work to its position within the heel band. The present invention accordingly provides novel means for clamping the heel part against the form and 50 maintain it in proper relation to the form and the insole as the work support receives its work-presenting movement. In a machine of the illustrated type the work support or jack is mounted for swinging movement in a direction lengthwise 55 of the form to present the work; and for the

purposes in view the construction herein shown comprises a device arranged to engage and clamp the work only after the work support has received a portion of its swinging movement, the device being thereafter yieldingly movable about a different axis than the work support in response to pressure of the work thereon during the remainder of the swinging movement of the work support. A machine of the illustrated type further comprises means for moving a portion of the work support upwardly to raise the work substantially at the end of the swinging movement of the support, and the invention further provides a novel construction such that the clamping device is movable upwardly with the work. Insurance is thus afforded that the heel part of the upper will not be displaced from its proper position before it is clamped by the heel band. The clamping device which thus moves with the work is so formed as to permit it to lie within the heel band without interfering with the clamping action of the band.

The novel features of the invention, including various novel details of construction and combinations of parts, will now be more particularly described with reference to the accompanying drawings and thereafter pointed out in the claims.

In the drawings,

Fig. 1 is a view partly in right-hand side elevation and partly in section of a portion of a machine of the illustrated type with the present invention embodied therein, showing the parts as they appear after the work-presenting movement of the work support and after the inward movement of the wipers;

Fig. 2 is a view similar to Fig. 1 of a portion of the structure there shown, but with the parts positioned as they appear prior to the work support has received a portion only of its work-presenting movement;

Fig. 3 is a view similar to Fig. 2, but showing the parts as they appear prior to the work-presenting movement of the work support;

Fig. 4 is a view mainly in front elevation of the novel work-clamping means provided by the invention;

Fig. 5 shows the work-clamping means partly in plan and partly in section on the line V—V 50 of Fig. 4;

Fig. 6 is a perspective view of the molded heel part of an upper before it is assembled with an insole on a form; and

Fig. 7 is a perspective view of the work as it 55

appears after it has been operated upon by the machine.

As more fully disclosed in the previously mentioned Letters Patent, a machine of the illustrated type comprises, for lasting the heel end of a shoe, a heel band 2 which is formed to embrace the heel end of the upper and is closed at a predetermined time in the operation of the machine to clamp the upper against the last, a 10 pair of wipers 4 (only one of which is herein shown) for wiping the margin of the heel end of the upper inwardly over the insole, and upper-fastening means comprising a plurality of tack drivers 6 carried inwardly by the wipers and 15 movable downwardly to drive a row of tacks through openings in the wipers to fasten the margin of the upper to the insole around the end and along the sides of the heel portion of the insole, the relation of the upper-fastening means 20 to the wipers being more particularly disclosed in Letters Patent No. 1,852,015. The work is mounted on a work support or jack 8 comprising a casting 10 mounted on a shaft 12 for swinging movement to carry the work to a position 25 within the heel band and a post 14 movable upwardly and downwardly in the casting 10 and provided at its upper end with a pin 16 arranged to enter the spindle hole in the heel end of the last. Fast on the post 14 is an arm 18 which 30 serves as a support for a toe rest 20 under the toe end of the last. Before starting the power operation of the machine the operator swings the jack rearwardly by hand to carry the work to its position within the heel band, and by depression of a treadle 22 raises the post 14 to force the work upwardly against a holdown 24 which 35 engages the insole and thereby determines the position of the work heightwise relatively to the wipers 4. The treadle 22 is connected by a link 40 26 to a lever 28 mounted on the lower end of the casting 10, the front end of this lever underlying the lower end of a rack bar 38 which has an upward extension 32 supporting the post 14. It will be understood that by the depression of the 45 treadle 22 the front end of the lever 28 is raised to impart the upward movement to the rack bar and the post. Thereafter, in the power operation of the machine, the jack casting 10 and the post 14 are controlled automatically by mechanism 50 constructed substantially as disclosed in Letters Patent No. 1,558,737. For this purpose a cam-operated slide 34 is arranged to impart swinging movement to a bell-crank lever 36 connected by a link 38 to pawl-and-ratchet mechanism 40. Through the action of this pawl-and-ratchet mechanism a rack bar 42 pivotally connected at 44 to the jack casting 10 is operated by a pinion 46 to impart further rearward swinging movement to the jack and thus to force the 55 work firmly against the heel band 2. The bell-crank lever 36 is connected by another link 48 to pawl-and-ratchet mechanism 50 through which a pinion 52 on the shaft 12 is operated to raise the rack bar 38 and the post 14 and thus to 60 force the work more firmly up against the holdown 24. The work is thus pressed against the holdown yieldingly through a spring 54 controlling two relatively movable portions of the link 48. For a more complete understanding of the 65 construction thus far described and of other characteristics of machines of the illustrated type the previously mentioned Letters Patent may be consulted.

In a type of shoe in frequent use at the present 70 time the heel part of the upper is unattached to

the forepart and is, in fact, often separated a substantial distance lengthwise of the shoe from the forepart portion. In the manufacture of shoes of that type it is a common practice to mold the heel portion of the upper materials substantially in the shape required for the finished shoe before assembling them with the insole. Such a molded heel part is shown at 56 in Fig. 6 and includes an inturned flange 58 formed to lie over the insole. It will be evident that preparatory to the fastening of such a molded heel part to the insole, as by fastenings driven through the flange 58, all that is necessary is to position the heel part in proper relation to the insole and to a last or other form on which the insole is mounted. For this fastening operation a heel-end lasting machine of the illustrated type may be advantageously utilized, since the heel band 2 will clamp the heel part of the upper closely about the form, the wipers 4 will press the in-turned flange of the heel part closely down on the insole, and the tack drivers 6 will drive the row of tacks required to fasten the flange to the insole. It is, however, inconvenient, if not impracticable, for the operator to hold the molded heel part in proper relation to the form with his fingers until the work support has completed its work-presenting movement, since the heel band in its open position is spaced but little from the sides of the form. For purposes of the present invention the machine herein shown is accordingly provided with means for clamping the heel part of the upper against the form to maintain it in proper relation to the form as the work support receives its work-presenting movement. As herein illustrated, the form consists of an ordinary last on which the insole is fastened by tacks, but it will be understood that a suitable form differing from an ordinary last may be used instead, if desired. The clamping device comprises a thin metal plate 60 so shaped as to conform approximately to the curvature of the extreme heel end of the last both heightwise and widthwise thereof and preferably faced with a layer 62 of leather or other suitable material for engagement with the heel part of the upper without danger of marring the upper. The plate 60 is secured to the upper end of a slide 64 mounted for upward and downward movements in guideways formed in two upwardly extending arms 66 of a carrier 68. Threaded in this carrier (Fig. 4) are two screws 70 by which it is pivotally mounted on ears 72 formed on the forward end of a bracket 74. The bracket 74 is adjustably clamped on the rack bar 42 by a plate 76 and screws 78. A spring 80 mounted in a recess in the carrier 68 and engaging the bracket 74 tends to swing the carrier in one direction about the screws 70 and accordingly to hold the plate 60 yieldingly in clamping relation to the heel part of the upper after the heel part has been clamped by the plate. By means of a screw 82 threaded in the carrier 68 and a washer 84 between the lower end of the screw and the spring 80 the amount of clamping force applied by the plate 60 to the heel part of the upper may be varied by varying the compression of the spring. Cooperating with the spring 80 to determine the initial position of the carrier 68 and the plate 60 is a nut 86 threaded on a rod 88 which is fast on the bracket 74 and extends upwardly through an opening 90 in the carrier 68. In order not to interfere with the mounting of the work on the work support the nut 86 is preferably so adjusted that initially the plate 60 is 75

spaced somewhat rearwardly from the work, as illustrated in Fig. 3. The plate 60, therefore, does not clamp the heel part of the upper against the last until after the work support has begun its rearward swinging movement. It will be understood that while the plate 60 and the means supporting the plate on the rack bar 42 are moved bodily rearward with the rack bar during the swinging movement of the work support, the work nevertheless approaches the plate 60 until it is clamped by the plate by reason of the swinging movement of the work support about an axis located a considerable distance below the rack bar. After the clamping of the heel part of the upper by the plate 60 the carrier 68 swings about the screws 70 against the resistance of the spring 80 in response to the pressure of the work on the plate as the work support continues its swinging movement.

As previously explained, the operator not only swings the work support rearwardly to carry the work to a position within the heel band 2, but also raises the post 14 by means of the treadle 22 to position the work against the holdown 24. Such upward movement of the post may be begun before the swinging movement of the work support has been completed, although the work will preferably not be raised into actual engagement with the holdown until the work support arrives substantially at the end of its swinging movement. In order not to disturb the relation of the clamping plate 60 to the heel part 56, there is provided means for raising the plate with the work by upward movement of the slide 64. For this purpose the slide carries a yoke member 92 formed partially to embrace the post 14 and arranged to be engaged by a shoulder 94 on the post. The yoke member has formed thereon a stud 96 extending rearwardly through a slot 98 in the slide 64 and having threaded on its rear end a nut 100 whereby the yoke member is clamped adjustably to the slide. It will accordingly be understood that when the post 14 is raised it acts also to raise the slide 64 and the plate 60. Such upward movement of the slide is effected against the resistance of a spring 102 connected to a pin 104 on the slide and to a pin 106 on one of the arms 66. To determine adjustably the initial height of the plate 60 in accordance with the size of the shoe, a plate 108 is clamped by a screw 110 to one of the arms 66 and is arranged to be engaged by a lug 112 on the slide 64, this screw extending through a vertical slot 114 in the plate 108.

In the illustrated use of the machine constructed as described the operator mounts on the last pin 16 and the toe rest 20 a last with an insole 116 fastened by tacks on its bottom face, the shoe support 8 at that time occupying its initial forwardly inclined position, as shown in Fig. 3. He then places a molded upper heel part 56 on the heel end of the last with its flange 58 overlapping the insole and swings the work support rearwardly by hand, preferably holding the heel part in place with his fingers, as he may conveniently do, until it is carried by the work support into position to be clamped by the plate 60. During further rearward swinging movement of the work support thereafter the plate 60 and its holder 6 are swung about the screws 70 in response to pressure of the work on the plate, the latter being held in clamping relation to the heel part 56 by the spring 80. The operator may begin to raise the post 14 by means of the treadle 22 before the work support arrives at the end of its rearward swinging movement, as illustrated in Fig. 2, and will further depress the treadle thereafter to force the work upwardly until the insole engages the holdown 24. Since the yoke member 92 is in position to be engaged by the shoulder 94 on the post 14 even when the work support is in its initial position, as illustrated in Fig. 3, any upward movement of the post imparts a corresponding upward movement to the plate 60 so that the plate remains in the same relation heightwise of the last to the heel part 56 as the work is raised by the treadle. After the work has been presented as described, the operator starts the power operation of the machine. Shortly after the starting of the machine the work support is further operated through the pawl-and-ratchet mechanisms 49 and 50 to force the work more firmly back against the heel band and to press it firmly upward against the holdown 24, and the heel band is closed about the heel end of the last, pressing the molded heel part 56 close to the last and to the edge of the insole. The mechanism with which machines of the illustrated type are provided for controlling the holdown 24 will preferably be so adjusted that the holdown will receive no vertical movement in the course of the operation of the machine. After the closing of the heel band the wipers 4 receive their inward wiping movement over the insole and thereby press the inturned flange 58 close against the bottom face of the insole. Instead of being then retracted and moved inwardly again in the manner characteristic of machines of the illustrated type, the wipers may, by suitable alteration of the shape of the cam which operates them, be held stationary after their above-mentioned inward movement until the tack drivers 6 are operated to drive their tacks through the flange 58 and into the insole to fasten the flange to the insole. After the driving of the tacks the wipers are retracted and the other parts of the machine are returned to their starting positions, the work support being released to permit it to swing forwardly and to permit downward return movement of the post 14. The work, in the condition illustrated in Fig. 7, is then removed from the work support preparatory to further operations thereon in the manufacture of the shoe.

While the mechanism provided by this invention is herein shown and described as operating on the previously molded heel part of an upper, it will be understood that such mechanism may, if desired, be used in operating on any other kind of work where such use may be found advantageous.

Having described the invention, what we claim as new and desire to secure by Letters Patent of the United States is:

1. In a machine for fastening in lasted relation to insoles the previously formed heel parts of uppers unattached to the foreparts, a work support arranged to support a form with an insole and such a formed heel part of an upper mounted thereon, means for fastening said heel part to the insole around the end and along the sides of the heel portion of the insole, said work support being mounted for swinging movement in a direction lengthwise of the form to present the work to the fastening means, and a member into engagement with which the heel part of the upper is carried by such movement of the work support prior to the completion of that movement, said member being mounted to swing about a different axis than the work support throughout the remainder of said movement of the support while holding

the heel part of the upper clamped against the form.

2. In a machine for fastening in lasted relation to insoles the previously formed heel parts of uppers unattached to the foreparts, a work support arranged to support a form with an insole and such a formed heel part of an upper mounted thereon, means for fastening said heel part to the insole around the end and along the sides of the heel portion of the insole, a heel band for embracing the heel part of the upper and clamping it against the form, said work support being mounted for swinging movement in a direction lengthwise of the form to present the work within the heel band, and a member for engaging the heel part of the upper and clamping it against the end face of the form, said member being movable about a different axis than the work support in response to pressure of the work thereon as the work support is thus moved to present the work.

3. In a machine for fastening in lasted relation to insoles the previously formed heel parts of uppers unattached to the foreparts, a work support arranged to support a form with an insole and such a formed heel part of an upper mounted thereon, means for fastening said heel part to the insole around the end and along the sides of the heel portion of the insole, said work support being movable in a direction lengthwise of the form to present the work to the fastening means, a member pivotally connected to the work support for further moving it in that direction, and a device supported by said member for clamping the heel part of the upper against the form as the work support receives its work-presenting movement.

4. In a machine for fastening in lasted relation to insoles the previously formed heel parts of uppers unattached to the foreparts, a work support arranged to support a form with an insole and such a formed heel part of an upper mounted thereon, means for fastening said heel part to the insole around the end and along the sides of the heel portion of the insole, said work support being mounted for swinging movement in a direction lengthwise of the form to present the work to the fastening means, a member pivotally connected to the work support for further swinging it in that direction, and a device supported by said member for clamping the heel part of the upper against the form as the work support receives its work-presenting movement, said device being mounted to swing relatively to said member about a different axis than the work support while in clamping relation to the work.

5. In a machine for fastening in lasted relation to insoles the previously formed heel parts of uppers unattached to the foreparts, a work support arranged to support a form with an insole and such a formed heel part of an upper mounted thereon, means for fastening said heel part to the insole around the end and along the sides of the heel portion of the insole, said work support being mounted for swinging movement in a direction lengthwise of the form to present the work to the fastening means, and a device arranged to engage the heel part of the upper and clamp it against the form only after the work support has received a portion of its work-presenting movement, said device being movable about a different axis than the work support in response to pressure of the work thereon throughout the remainder of said movement of the support while

also moving bodily in the same direction as the support.

6. In a machine for fastening in lasted relation to insoles the previously formed heel parts of uppers unattached to the foreparts, a work support arranged to support a form with an insole and such a formed heel part of an upper mounted thereon, means for fastening said heel part to the insole around the end and along the sides of the heel portion of the insole, said work support being mounted for swinging movement in a direction lengthwise of the form to present the work to the fastening means, a member arranged to engage the heel part of the upper and clamp it against the form, said member being mounted to swing in directions lengthwise of the form about a different axis than the work support, a spring against the resistance of which the member is movable about its axis in response to pressure of the work against it as the work support receives its work-presenting movement, and means for positioning the member in such relation to the work support as to engage the work only after the beginning of the work-presenting movement of the support.

7. In a machine for fastening in lasted relation to insoles the previously formed heel parts of uppers unattached to the foreparts, a work support arranged to support a form with an insole and such a formed heel part of an upper mounted thereon, means for fastening said heel part to the insole around the end and along the sides of the heel portion of the insole, said work support being mounted for work-presenting movement in a direction lengthwise of the form and comprising a member movable also in an upward direction relatively to other portions of said support to raise the work, means for operating said member thus to raise the work substantially at the end of said work-presenting movement of the work support, and a device arranged to clamp the heel part of the upper against the form during a substantial portion of said work-presenting movement of the support, said device being movable with the work in both said directions.

8. In a machine for fastening in lasted relation to insoles the previously formed heel parts of uppers unattached to the foreparts, a work support arranged to support a form with an insole and such a formed heel part of an upper mounted thereon, means for fastening said heel part to the insole around the end and along the sides of the heel portion of the insole, said work support being mounted for work-presenting movement in a direction lengthwise of the form and comprising a member movable also in an upward direction relatively to other portions of said support to raise the work, means for operating said member thus to raise the work substantially at the end of said work-presenting movement of the work support, a device arranged to engage the heel part of the upper and clamp it against the form, said device being movable with the work as the work support is moved in the direction lengthwise of the form, and means arranged to be operated by the upward movement of said member to raise said device with the work.

9. In a machine for fastening in lasted relation to insoles the previously formed heel parts of uppers unattached to the foreparts, a work support arranged to support a form with an insole and such a formed heel part of an upper mounted thereon, means for fastening said heel part to the insole around the end and along the sides of the heel portion of the insole, said work support being

mounted for work-presenting movement in a direction lengthwise of the form and comprising a member movable also in an upward direction to raise the work, means for operating said member thus to raise the work substantially at the end of said work-presenting movement of the work support, a device arranged to engage the heel part of the upper and clamp it against the form, said device being arranged to engage the work only after the work support has received a portion of its movement in the direction lengthwise of the form and being thereafter movable with the work during further such movement of the work support, and means for raising said device with the work.

10. In a machine for fastening in lasted relation to insoles the previously formed heel parts of uppers unattached to the foreparts, a work support arranged to support a form with an insole and such a formed heel part of an upper mounted thereon, means for fastening said heel part to the insole around the end and along the sides of the heel portion of the insole, said work support being mounted for swinging movement in a direction lengthwise of the form from work-receiving position and comprising a member movable also in an upward direction to raise the work, and a device arranged to engage the heel part of the upper and clamp it against the form as the work support receives its swinging movement, said device being movable about a different axis than the work support while in clamping relation to the work and being also movable upwardly with the work.

11. In a machine for fastening in lasted relation to insoles the previously formed heel parts of uppers unattached to the foreparts, a work support arranged to support a form with an insole and such a formed heel part of an upper mounted thereon, means for fastening said heel part to the insole around the end and along the sides of the heel portion of the insole, said work support being mounted for swinging movement in a direction lengthwise of the form from work-receiving position and comprising a member movable also in an upward direction to raise the work, a device arranged to engage the heel part of the upper and clamp it against the form only after the work support has received a portion of its swinging movement and movable thereafter about a different axis than the work support as the latter continues its swinging movement, means for raising said device with the work by the upward movement of said member, and a spring against the resistance of which the device is thus movable upwardly with the work.

12. In a machine for fastening uppers to insoles, the combination with upper-fastening means, of a work support arranged to support a form with an upper and an insole thereon and mounted for swinging movement in a direction lengthwise of the form from work-receiving position, and a device arranged to engage the heel

end of the upper and clamp it against the form as the work support receives its swinging movement, said device being mounted to swing about a different axis than the work support in response to pressure of the work thereon while thus engaging the upper.

13. In a machine for fastening uppers to insoles, the combination with upper-fastening means, of a work support arranged to support a form with an upper and an insole thereon and mounted for swinging movement in a direction lengthwise of the form from work-receiving position, a device arranged to engage the heel end of the upper and clamp it against the form only after the work support has received a portion of its swinging movement and movable thereafter about a different axis than the work support in response to pressure of the work thereon as the work support continues its swinging movement, and spring means against the resistance of which said device is thus movable about its axis.

14. In a machine for fastening uppers to insoles, the combination with upper-fastening means, of a work support arranged to support a form with an upper and an insole mounted thereon, a heel band, said work support being mounted for work-presenting movement in a direction lengthwise of the form to position the work within the heel band and comprising a member movable also in an upward direction to raise the work, means for operating said member thus to raise the work substantially at the end of said work-presenting movement of the work support, and a device arranged to clamp the heel end of the upper against the form, said device being movable in a direction lengthwise of the form in response to pressure of the work thereon as the work support receives its movement in that direction and being also movable upwardly with the work when the latter is raised by said member.

15. In a machine for fastening uppers to insoles, the combination with upper-fastening means, of a work support arranged to support a form with an upper and an insole mounted thereon, said work support being mounted for swinging movement in a direction lengthwise of the form from work-receiving position and comprising a member movable also in an upward direction to raise the work, means for operating said member thus to raise the work substantially at the end of said swinging movement of the work support, a device arranged to engage the heel end of the upper and clamp it against the form only after the work support has received a portion of its swinging movement and movable thereafter about a different axis than the work support in response to pressure of the work thereon as the work support continues its swinging movement, and means for raising said device with the work by the upward movement of said member.

KARL ENGEL.
CHARLES S. KINNEY.

CERTIFICATE OF CORRECTION.

Patent No. 2,165,361.

July 11, 1939.

KARL ENGEL, ET AL.

It is hereby certified that error appears in the printed specification of the above numbered patent requiring correction as follows: Page 4, second column, line 21, claim 6, for the word "work-pressing" read --work-presenting--; and that the said Letters Patent should be read with this correction therein that the same may conform to the record of the case in the Patent Office.

Signed and sealed this 7th day of May, A. D. 1940.

(Seal)

Henry Van Arsdale,
Acting Commissioner of Patents.
